UNITED STATES PATENT OFFICE

GEORGE F. JACKSON, OF BALTIMORE, MARYLAND, ASSIGNOR TO CONTINENTAL CAN COMPANY, INC., OF NEW YORK, N. Y., A CORPORATION OF NEW YORK

SEAMING HEAD FOR CAN-CLOSING MACHINES

Application filed February 23, 1927. Serial No. 170,282.

This invention relates to new and useful improvements in seaming heads for can closing machines, and more particularly to a seaming head provided with a chuck and a body portion rotatable relative thereto, which body portion carries seaming rolls for rolling the can end and flange on the can body into a double seam.

An object of the invention is to provide a seaming head of the above type wherein the seaming roll is mounted on the support therefor, so that it is free to rotate and move sideways during the forming of the seam, whereby said seaming roll may be caused to impinge on the chuck and rotation thus imparted to said seaming roll.

A further object of the invention is to provide a seaming head of the above type wherein the seaming roll is held on its support solely by inter-engagement with the chuck.

A still further object of the invention is to provide a seaming head of the above type with a removable plate at the lower face thereof for closing the opening through the seaming roll so as to hold the roller bearing in place and prevent the lubricant therefor from escaping.

These and other objects will in part be obvious and will in part be hereinafter more fully disclosed.

In the drawings—

Figure 1 is a sectional view through a seaming head embodying my improvements, the section being taken through the first operation rolls;

Fig. 2 is a similar view through the seaming head taken through the second operation rolls;

Fig. 3 is an enlarged detail showing a portion of the can, the chuck and the seaming roll at the completion of the first operation, and

Fig. 4 is a similar view at the completion of the second operation.

The invention is directed to a seaming head having a rotating chuck and seaming rolls which have inter-engaging parts. Either the chuck is rotated to rotate a can which is to be closed, or, if the chuck is stationary, then the body portion of the head is rotated, which causes the seaming rolls to travel about the

can. The seaming rolls are preferably carried by levers which are cam-actuated for bringing the seaming rolls into contact with the can end and for rolling the can end, together with the flange on the can body into a double seam. The first operation rolls are brought into contact with the can end and the first operation completed; then the second operation rolls are brought into engagement with the seam for finishing the closing of the seam. The invention is particularly directed to the manner of mounting the seaming rolls on the seaming levers. The seaming roll is mounted on the seaming lever so that it is capable of moving endwise, that is, endwise of the lever, and said seaming rolls are held on their respective levers by their inter-engagement with the chuck. Each seaming lever carries a supporting stud for the seaming roll, and a roller bearing is placed on this stud, and a seaming roll slipped over the roller bearing.

This is accomplished when the seaming lever is moved outwardly so as to permit the movement of the seaming roll sideways, or endwise of the lever, into proper position so as to engage the chuck. Then the seaming lever is returned to its normal position, and the seaming roll is held on this stud by the chuck. A plate is inserted in a suitable recess in the lower face of the seaming roll, and this plate serves to hold the roller bearings in place and prevent the escape of the lubricant for the seaming roll. During the seaming operation, there is always a thrust produced on the seaming roll through the rolling of the metal into the double seam. This thrust is in a downward direction. The downward thrust on the seaming roll will tend to move said seaming roll along the roller bearing endwise of the seaming lever, until the flange on the seaming roll impinges against the projecting flange on the chuck. This brings about a frictional engagement between the chuck and the seaming roll, so that if the chuck is rotating, it will

drive the seaming roll, and if the chuck is stationary, and the seaming roll traveling bodily around the chuck, again the seaming roll will be caused to rotate. The advantage of this frictional drive of the seaming roll by the chuck is to insure that the seaming roll shall

always be rotating and not come to a standstill so as to slip over the seam and thus produce a dead head.

Referring more in detail to the drawings, 5 the seaming head includes a body portion 1 on which is mounted a chuck 2. This chuck is rotatable in a bearing 3. A spindle is attached to the chuck for rotating the same. Instead of rotating the chuck, the body portion 10 of the head may rotate about the chuck, in which case, the spindle will be used to hold the chuck from rotation. It is essential that either the body portion of the head rotate, carrying the seaming rolls mounted thereon 15 around the can, or that the chuck rotate, in which case the head is held stationary, and the can is rotated within the seaming rolls. The seaming rolls, according to the present embodiment of the invention, are mounted on levers. These levers are arranged in pairs, 20 and each lever carries a seaming roll. In Fig. 1 there is shown the levers 4, 4 which carry the seaming rolls 5, 5. These are the first operation rolls. In Fig. 2 there are levers 25 6, 6 which carry seaming rolls 7, 7, and these are the second operation rolls. Each lever is pivoted at 8; and is swung on its pivot by a cam 9 which is mounted on the seaming head so that it may be moved longitudinally of the 30 chuck spindle. This cam engages a member 10 when it is moved in an endwise direction and swings the lever outwardly at its upper end, thus causing the seaming roll to engage the can end and roll the end and flange on the 35 can end into a seam. The second operation rolls are each pivoted at 11 and operated by a cam 12 which engages a member 13^a carried by the seaming lever. This cam 12 moves the upper end of the lever outwardly and 40 brings the second operation rolls into engagement with the seam for performing the finishing operation on the seam. It is understood, of course, that the first operation rolls perform their function, after which they are 45 retracted and the second operation rolls are brought into action.

The structure of the seaming head described above, and one method of operating the same, is shown and described in the patent granted

20 I. F. Warne, June 24, 1919, No. 1,307,888, and further detail description thereof is not thought necessary.

The chuck 2 is provided with a portion 13 which is adapted to seat within the recess of 55 the can end which is to be attached to the can body. The chuck is provided with an annular groove 14, and with a projecting annular portion 15 at the upper side of this groove 14. Each seaming roll is provided with an annular 60 groove 16, thus forming spaced projecting members 17 and 18. The seaming roll is also provided with a seaming groove 19. The annular groove 16 receives the projecting portion 15 of the chuck and this forms the inter- 65 engagement between the chuck and the seam-than in the first operation, but whenever it

ing roll. It will be noted that the member 17 on the seaming roll overlies the projecting member 15 on the chuck. These parts are thus inter-engaged throughout the entire operation of the seaming head. When the machine 70 is stopped, the seaming lever, however, may be disconnected from the head or may be constructed to move so as to bring the seaming roll out of engagement with the chuck. The seaming lever is provided with a supporting 75 stud or member 20 which is secured to the seaming lever by means of a nut 21. This supporting stud 20 is solid throughout. The roller bearing 22 fits on over the stud. The stud is shouldered as indicated at 23, which 80 shoulder bears against a hardened plate 24^a attached to the seaming lever, and the nut 21 draws the shoulder up against the seaming lever. This makes a rigid support for the supporting stud 20. The seaming roll is provided with an opening 24, and this opening is of proper size so that the seaming roll may be slipped on over the roller bearing 22. The seaming roll is placed on the roller bearing, or the seaming roll with the roller bearing 85 placed on the stud, when the seaming lever is moved outwardly at its lower end, so as to permit the seaming roll to pass the projection on the chuck. When the seaming lever is brought back into normal position, then the 90 projecting member 15 on the chuck will enter the annular groove 16 of the seaming roll and hold the seaming roll on the seaming lever. This is the only means of holding the seaming roll on the supporting stud therefor, and 95 otherwise, the seaming roll is free to move sidewise or endwise of the lever. It is, of course, free to rotate on the lever. The lower face of the seaming roll is provided with a recess which is undercut, and a plate 25 is 100 forced into this recess. The plate has a tapered edge, and when forced into the recess, will be held therein through engagement with the undercut edge on the seaming roll. This plate is for the purpose of preventing the roller bearing from dropping out, and also for 105 preventing the lubricant which is fed to the roller bearing through the passage 26 from a lubricating chamber 27.

In an ordinary seaming head, the seaming roll is caused to rotate through the frictional contact of the seaming roll with the metal of the can end. When the can body and can end are rotated, then this frictional contact will produce a rotation of the seaming roll. Likewise, when the can body is stationary, the rotation of the seaming head about the can and the bodily traveling of the seaming rolls around the end of the can will, through the frictional engagement of the seaming roll 120 with the metal of the can end, cause the roll to rotate. It sometimes happens that the seaming roll stops rotating. This possibly occurs more often in the second operation 125 than in the first operation, but whenever it 130

occurs, then the seaming roll slides along the metal instead of rolling up on to the metal, and this is apt to result in a bad seam, often referred to as a dead head.

5 In applicant's seaming head, where the seaming roll is free to move endwise of the seaming lever, the thrust on the seaming roll incident to the rolling of the metal into the seam, is in a downward direction, and this 10 downward thrust on the seaming roll will cause the projecting portion 17 on the seaming roll to engage the projecting portion 15 of the chuck. This causes the seaming roll to impinge on the chuck, and the chuck to 15 frictionally drive the seaming roll through this impinging contact. If the chuck is rotating, this will impart through this impinging contact, a frictional drive to the roll. If the chuck is stationary, then the bodily travel 20 of the roll will cause said roll to rotate through this frictional impinging contact. In other words, in applicant's seaming head, it is not the contact of the seaming roll with the metal alone that causes the roll to rotate, 25 but the impinging contact of the seaming roll with the chuck also aids in the rotating of the seaming roll. The harder the thrust on the seaming roll during the forming of the seam, the harder will be the impinging contact of 30 the seaming roll with the chuck. By the use of my improved seaming head, the seaming roll will always be caused to rotate during the forming of the seam, and imperfect seams due to the stopping of the rotation of the roll 35 are avoided.

It is obvious that minor changes in the details of construction and the arrangement of the parts may be made without departing from the spirit of the invention as set forth in 40 the appended claims.

Having thus described the invention, what I claim as new and desire to secure by Letters-Patent, is—

1. A seaming head for closing machines 45 including a chuck for engaging a can end and holding the same on the can body, a body portion, said chuck and body portion having a relative rotation, seaming levers carried by said body portion, a seaming roll mounted to 50 rotate freely on said seaming lever, said seaming roll having a seam forming groove and a portion above said groove and spaced therefrom adapted to overlie said chuck, said seaming roll being mounted on said seaming lever 55 so as to move freely endwise of the lever whereby the thrust on the seaming roll incident to the forming of the seam will cause the overlying portion of the roll to impinge upon said chuck and be rotated thereby.

60 2. A seaming head for closing machines including a chuck for engaging a can end and holding the same on the can body, a body portion, said chuck and body portion having a relative rotation, seaming levers carried by 65 said body, a seaming roll mounted to rotate

freely on the seaming lever, said seaming roll having a seam forming groove and an annular groove formed therein separate from the seaming groove, said chuck having an annular projecting portion adapted to engage in 70 said annular groove, said projecting portion and groove being of such dimensions as to maintain their engagement throughout the normal operation of the seaming head, said seaming roll being free to move endwise of 75 said seaming lever and held thereon by the chuck whereby the thrust on the seaming roll incident to the forming of the seam will cause the roll to impinge upon the chuck and rotate.

3. A seaming head for closing machines including a seaming lever, a seaming chuck, a seaming roll, a solid supporting stud for said seaming roll carried by the seaming lever, a roller bearing on said stud between the stud and the seaming roll, said seaming roll having a seam forming groove and a portion above said groove and spaced therefrom adapted to overlie said chuck whereby the thrust on the seaming roll incident to forming of the seam will cause the overlying portion of the roll to impinge upon said chuck and be rotated thereby, said seaming roll having a recess in its under face and a plate secured in said recess and covering the opening in the seaming roll for the roller bearing and 95 stud.

In testimony whereof, I affix my signature.
GEORGE F. JACKSON.
